UNITED STATES PATENT OFFICE.

ARNOLD F. MOLLRING, OF NEBRASKA CITY, NEBRASKA.

IMPROVEMENT IN CLOTH-MEASURING MACHINES.

Specification forming part of Letters Patent No. **222,931**, dated December 23, 1879; application filed August 28, 1879.

To all whom it may concern:

Be it known that I, ARNOLD F. MOLLRING, of Nebraska City, in the county of Otoe and State of Nebraska, have invented a new and valuable Improvement in Machines for Rolling Goods with Measuring-Slips; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my improved machine. Fig. 2 is a top view thereof. Fig. 3 is a longitudinal vertical section of the same; and Figs. 4, 5, 6, 7, 8, 9, and 10 are details.

This invention has relation to improvements in machines for measuring the contents of a roll of dry-goods, carpet, matting, and the like, and for rolling up therewith a measuring-strip of suitable material, laid off in yards, half-yards, quarters, and other fractions of a yard.

The nature of the invention will be herein-after fully set forth.

In the annexed drawings, the letter A designates a strong wooden or metallic frame, the side bars of which are raised or arched, as indicated at *a*, and afford bearings to a measuring-roller, B, of eighteen inches in circumference, though it may be a full yard or any desired fractional part thereof, as a quarter or eighth yard. In close proximity to this roller is a smaller roller, C, which may be denominated the "tightener," that may also be journaled in the part *a* of the frame. These rollers are generally about thirty-seven inches in length, but may be made shorter or longer, as required by the width of the goods.

One of the journals of the measuring-roller has secured upon its end outside of the frame a finger or gear, *b*, that engages a notched graduated disk, D, having its bearings in said frame, and graduated in half-yards and fractions thereof when the roller B is one half-yard in circumference, but in yards and divisions thereof when the said roller is a yard in circumference.

It is clear that at each revolution of meas-

uring-roller, it being eighteen (18) inches in circumference, one half-yard will have been paid off. The finger *b* is in the nature of a cross-head, and as the measuring-roller turns over at each complete revolution, the dial will indicate a corresponding measurement—namely, a half-yard. Should the measuring-roller be a yard in circumference, its complete rotation will indicate a yard upon the dial.

The goods to be measured are usually wound upon a board, *c*, the ends of which project and are secured in the clamps D. These clamps rotate in bearings in one end of frame A, and they embrace the ends of the board *c*. The material is thence passed under and around the tightening-roller, thence under and above and around the measuring-roller, and thence downward to a receiving device, E. This is composed of a board, *c'*, and two rotary clamps, H H', each having its bearings in the sides of the frame and designed to clasp the ends of said board.

Extending across the frame A is a metallic bridge, F, upon which is a laterally-adjustable reel, G, upon which is wound a paper strip, G', graduated for yards and fractional portions thereof, and made of any sufficiently tough material, usually paper. The ends of the strip and of the goods are brought together and secured to the board *c'*. The clamp H' has upon one end a gear-wheel, *d*, that engages a larger gear, *d'*, having its bearings in the sides of the frame, and actuated by a crank-arm or other equivalent device, *d''*. The goods are wound up, as the crank is actuated, in an equal degree with the measuring-strip aforesaid. Consequently the contents of the goods will be indicated both on the dial and on said strip. Hence, by noting the contents of the roll in yards, as the fractional parts are disposed of, any desired measurement may be arrived at.

This device may also be used as a ribbon-roller by inserting the spurred heads L in opposite sides of the frame and placing the ribbon-block between them.

When goods are wound in a roll without a center-board I employ the device indicated in Fig. 6, consisting of a spindle, *q*, of flat form transversely, having at one end a journal, *q'*,

a head, q^2 , and at the other end a tapering rounded point, q^3 , forming a journal, q^3 . This device is thrust through the bolt of cloth longitudinally, and substituted for the clamp device D.

The spindles from which the materials are unwound, and upon which they are wound, may be constructed of two longitudinal sections, clamped together at their ends and clipping the ends of the goods between them. These spindles have suitable independent bearings in the frame, or may use and occupy the bearings of the spindles of which they are the substitutes. This modification is illustrated in Fig. 7 at N. The push-spindle N' (shown in Fig. 4) may be also used to clamp the ends of a board by passing thereon the clamps o.

As shown in Fig. 3, the measuring-strip is prevented from unwinding too fast—that is, beyond the rate at which the goods are rolled up on the receiving-spindle—by means of a metallic spring, y, secured at one end to the frame of the reel, and bearing at the other on the roll of measuring-strip.

The tightening-roller is journaled in a vibrating metallic frame, X, pivoted to the main

frame and extending up a sufficient distance to be out of the way. Frame X is locked to the bridge F, supporting the reel, by means of a laterally-adjustable catch, z, arranged on said bridge and engaging the top bar of said frame, as shown. By throwing up the latch and lowering the vibrating frame the tightening-roller is retracted from the measuring-roller, and the goods readily passed between them.

What I claim as new, and desire to secure by Letters Patent, is—

The combination, with the rolls D and E, carrying the cloth, the measuring-roll ~~D~~^B, and tightening-roll ~~E~~^C of the laterally-adjustable roll G, carrying the measuring-strip G', the whole adapted to operate in such manner as to wind the measuring-strips together in one bolt, substantially as specified.

In testimony that I claim the above I have hereunto subscribed my name in the presence of two witnesses.

ARNOLD FREDRICK MOLLRING.
